CLAIM

The ornamental design for a motorbike handlebar clamp mechanism, as shown and described.

DESCRIPTION

FIG. 1 is a top perspective view showing environmental structure of the top, rear, and right sides of a motorbike handlebar clamp mechanism;

FIG. 2 is a top perspective view showing environmental structure of the top, front, and left sides of the motorbike handlebar clamp mechanism;

FIG. 3 is a top perspective view showing the top, front, and left sides of the motorbike handlebar clamp mechanism;

FIG. 4 is a top perspective view showing the top, rear, and right sides of the motorbike handlebar clamp mechanism;

FIG. 5 is a right side elevation view of the motorbike handlebar clamp mechanism;

FIG. 6 is a left side elevation view of the motorbike handlebar clamp mechanism;

FIG. 7 is a front elevation view of the motorbike handlebar clamp mechanism;

FIG. 8 is a rear elevation view of the motorbike handlebar clamp mechanism;

FIG. 9 is a top plan view of the motorbike handlebar clamp mechanism; and,

FIG. 10 is a bottom plan view of the motorbike handlebar clamp mechanism.

The broken line showing of portions of the motorbike are provided for the purpose of illustrating environmental structure and form no part of the claimed design.

1 Claim, 6 Drawing Sheets
